UNITED STATES PATENT OFFICE.

LEON BLUMENTAHL AND JOHN GALE STEELE, OF KANSAS CITY, MISSOURI,
ASSIGNORS OF ONE-THIRD TO MORRIS R. COHEN, OF SAME PLACE.

MEDICAL COMPOUND.

SPECIFICATION forming part of Letters Patent No. 363,448, dated May 24, 1887.

Application filed November 1, 1886. Serial No. 217,712. (No specimens.)

To all whom it may concern:

Be it known that we, LEON BLUMENTAHL and JOHN GALE STEELE, of Kansas City, Jackson county, Missouri, have invented a new and 5 Improved Medical Compound, of which the following is a full, clear, and exact description.

Our invention relates to a novel remedy for diarrhea, dysentery, colic, and all such diseases of the stomach and bowels, and to the 10 method of using the same, substantially as hereinafter set forth.

The compound and the method of making and using it are fully described in the following specification.

15 The compound is composed of the ingredients in about the proportions and quantities stated, but the process of compounding them may be varied as may be desired.

To prepare the compound, we take two 20 ounces of beef-gall, which should be procured as fresh as possible; one ounce of digitalis; one ounce of valerian, which may be either in its natural state or it may be in powdered form; one ounce sulphate of potash; one ounce peppermint-leaves; one dram opium; two pints 25 of alcohol; one-half ounce of gum-asafetida, and one pint of old wine, which latter may be of any desired brand. Of these we form a tincture by mixing and allowing the mixture to 30 stand in a warm place for about five days, after which time it is ready to be used.

Our method of using this compound is as follows: We prepare a band or bandage of flannel or of some suitable goods and immerse 35 it in the tincture for a period of about ten hours. Said band or belt of flannel is then re-

moved from the tincture, and dried in some way that will not disperse any of the medical properties which are held by it—that is, it should not be dried in the sunshine, nor by 40 the fierce heat of a stove or furnace, but rather it should be allowed to remain in a comparatively cool place until perfectly dry. The flannel bandage thus prepared and charged with the tincture is then to be applied to the 45 stomach of the patient, and secured thereon by means of suitable straps or strings, and permitted to remain from, say, one hour to three days, or until he obtains the desired relief. Used in this way we can say that the compound will remedy the most aggravated case 50 of diarrhea.

The action of the compound is quite mild and soothing, and hence it can be used by or upon a child only three months of age; or it 55 may be used with much success by the oldest persons.

Having thus described our invention, what we claim is—

The local remedy for diarrhea, &c., consisting of beef-gall, digitalis, valerian, sulphate of potash, peppermint, opium, asafetida, alcohol, and wine, in the proportions substantially as set forth.

In testimony whereof we affix our signatures 65 in presence of two witnesses.

LEON BLUMENTAHL
JOHN GALE STEELE.
